UNITED STATES PATENT OFFICE.

BOUDINOT G. LEAKE, OF FORT WORTH, TEXAS, ASSIGNOR OF ONE-HALF TO B. V. CUMMINS,
OF WAURIKA, OKLAHOMA.

PORTABLE CONCRETE-MIXER

No. 914,291.

Specification of Letters Patent.

Patented March 2, 1909.

Application filed August 18, 1908. Serial No. 449,141.

To all whom it may concern:

Be it known that I, BOUDINOT G. LEAKE, a citizen of the United States, residing at Fort Worth, county of Tarrant, and State of Texas, have invented a Portable Concrete-Mixer, of which the following is a specification.

This invention relates to a device for mixing materials for making plastic compositions, and more particularly to a device for mixing and delivering the material in one operation, and the object is to provide devices which will automatically mix the material while transporting the material where it is to be used and to provide a truck adapted to carry the mixer and to operate the same while delivering the material and from which the mixer may be suspended when it is not desirable to operate the mixer and which truck may be rotated by one wheel while the other wheel stands fixed to its axle.

Other objects and advantages will be fully explained in the following description and the invention will be more particularly pointed out in the claims.

Reference is had to the accompanying drawings which form a part of this application and specification.

Figure 1 is a perspective view of the machine. Fig. 2 is a vertical section of the device from front to rear. Fig. 3 is a vertical cross section of the same. Fig. 4 is a detail view of the combined handle and hasp. Fig. 5 is a detail view of the lock which is used to lock the mixer to the truck-wheel temporarily. Fig. 6 is an enlarged detail of the hasp and handle, showing the manner of attaching the same to the mixer. Fig. 7 is a detail sectional view, showing the manner of hinging the door of the mixer to the body portion. Fig. 8 is a sectional view, showing the manner of locking one wheel to the axle for the purpose of rotating the mixer without moving its location.

Similar characters of reference are used to indicate the same parts throughout the several views.

The improved mixer is provided with a two-wheeled truck having wheels 1 and 2, an axle 3 and a bail or handle 4 by which the truck can be pushed or pulled. The mixer is provided with a sleeve 5 which extends centrally through the mixer and is attached to the flanged collars 17 and serves to prevent

the axle. The mixer may be of any suitable design. I show a rectangular box or trough 6 which is provided with a door 7 hinged thereto by hinges 18. Normally the box 6 or mixer hangs loosely on the axle 3. A locking bar 8 is slidably mounted on the front of the machine or mixer for temporarily locking the mixer to one of the wheels. This locking bar is held on the mixer by keepers or loops 9, and is provided with a groove 16 in the end for receiving a spoke of the wheel. The locking bar 8 may be further secured in place by a thumb bolt 10 which screws through the bar and presses against the side of the box. The locking bar is located on the front of the mixer for the convenience of the operator. The lid 7 is hinged to the mixer at the rear upper part and extends forward. The lid is locked to the mixer by hasps 11 which are hinged to the lid and engage staples 12 inserted in the front side of the mixer. The hasps are provided with loops 13. The object of these provisions is that when the truck is brought up to place where the material is to be used, the operator may release the hasps and pull the lid forward. This will tilt the mixer and dump the material out. The locking bar 8 must first be released from the wheel.

If it is not desirable to transport the mixed material to a different location, one wheel of the truck may be locked to the axle by a set screw 14. When the mixer is charged the truck may be rotated, one wheel rotating without turning while the other wheel revolves. The mixer will thus be revolved by one wheel while the other wheel simply rotates without turning on the axle.

As an agitating means, bars 15 may be attached to the interior of the mixer. These bars will serve to mix or jumble the material as the mixer is revolved by the wheel truck.

The operation is simple. The proper ingredients are placed in the mixer at the supply source. The mixer is then closed and locked to one of the truck wheels. By the time the material is transported in the wheeled truck to the place in which it is to be used, the material is thoroughly mixed. The material is discharged from the mixture as above described.

Having fully described my invention, what I claim as new and desire to secure by Letters Patent, is,—

1. A concrete mixer comprising a wheeled truck provided with an axle, a receptacle

having a sleeve extending centrally therethrough and engaging said axle loosely, a hinged lid closing said receptacle, and a sliding bar mounted on the front of said mixer and adapted to lock said receptacle to one of said wheels whereby said receptacle may be revolved in either direction.

2. A concrete mixer comprising a wheeled truck provided with an axle, a receptacle having a sleeve extending centrally therethrough and engaging said axle loosely, a sliding bar mounted on the front of said receptacle and adapted to lock said receptacle to one of said wheels to revolve said receptacle in either direction; a hinged lid closing said receptacle, and hasps and staples for locking the free edge of said lid to the front of said receptacle, said hasps having loops constituting handles for said receptacle for dumping material from said receptacle.

3. A mixer for plastic material comprising a wheeled truck provided with an axle, a receptacle having a sleeve extending centrally therethrough and engaging said axle loosely, bars attached to the interior of said receptacle adapted to mix material therein during the moving of said receptacle, a sliding bar mounted on the front of said receptacle and adapted to lock said receptacle to one of said wheels, a hinged lid closing said receptacle, and hasps and staples for locking the free edge of said lid to said receptacle, said hasps having loops constituting handles for said re-

ceptacle for dumping material from said receptacle.

4. A concrete mixer comprising a wheeled truck provided with an axle, a receptacle having a sleeve extending centrally therethrough and engaging said axle loosely, a hinged lid closing said receptacle, a sliding bar mounted on said receptacle and adapted to lock said receptacle to one of the wheels of the truck, and means adapted to lock one of the wheels of the truck to the axle while the other wheel revolves about said axle.

5. A concrete mixer comprising a wheeled truck provided with an axle, a receptacle having a sleeve extending centrally therethrough and engaging said axle loosely, a hinged lid closing said receptacle, hasps and staples for locking the free edge of said lid to said receptacle, a handle for said receptacle formed on each hasp, a sliding bar for locking said receptacle to one of the wheels of said truck, and a draft bail engaging said axle for moving the mixer, said handles and said sliding bar being on the side of said receptacle adjacent to said bail.

In testimony whereof, I set my hand in the presence of two witnesses, this 6th day of August, 1908.

BOUDINOT G. LEAKE.
